UNITED STATES PATENT OFFICE

167,759

CABINET ELECTRIC AIR CIRCULATOR

Donald L. McFarland, Stratford, Conn., assignor
to General Electric Company, a corporation of
New York

Application December 12, 1951, Serial No. 17,698

Term of patent 14 years

(Cl. D26—7)

To all whom it may concern:

Be it known that I, Donald L. McFarland, a citizen of the United States, residing at Stratford, State of Connecticut, have invented a new, original, and ornamental Design for a Cabinet Electric Air Circulator, of which the following is a specification, reference being had to the accompanying drawing, forming a part thereof.

In the drawing: Fig. 1 is a perspective view from the front side of a cabinet electric air circulator, embodying my new design; and Fig. 2 is a similar view from the rear side.

I claim:

The ornamental design for a cabinet electric air circulator, substantially as shown.

DONALD L. McFARLAND.
